UNITED STATES PATENT OFFICE.

MAX BITTRICH, OF STETTIN, GERMANY.

FEEDING DEVICE FOR RETORTS AND THE LIKE.

No. 906,187.

Specification of Letters Patent.

Patented Dec. 8, 1908.

Application filed January 14, 1907. Serial No. 352,142.

To all whom it may concern:

Be it known that I, MAX BITTRICH, a subject of the Emperor of Germany, and a resident of Stettin, Germany, have invented certain new and useful Improvements in Feeding Devices for Retorts and the Like, of which the following is a specification.

My invention relates to devices for feeding the material to be treated to retorts and the like, particularly when such retorts are arranged in a plurality of rows.

The object of my invention is to provide a simple feed device of the above indicated character, in which provision is made for discharging material from the device to one side or the other so as to reach retorts of different rows.

Reference is to be had to the accompanying drawings illustrating two forms of my invention, and in which

Figure 1 is a side elevation showing my improved feed device in relation to two retorts, the parts being in the position of rest; Fig. 2 is a substantially central section 25 through such device taken at right angles to Fig. 1; Fig. 3 is a side elevation of a portion of the device in the operative position; Fig. 4 is a view corresponding to Fig. 1, but showing the parts in the operative position; Fig. 5 30 is a side elevation showing the second form of my invention in the position of rest; and Fig. 6 shows the said form in the operative position.

Referring to Figs. 1 to 4 inclusive, I have 35 shown a carriage I adapted to travel on suitable rails, so that it can be moved to different positions, and when the retorts are in rows extending parallel with the track on which the carriage runs, the relative position of 40 track and retorts is such that the carriage will be approximately midway between two adjacent rows of retorts, such as indicated at 36 and 37 in Fig. 1. The carriage comprises a box or receptacle having a bottom opening, 45 which in the position of rest is closed by a swinging gate 2, connected with a rock shaft 3, which may be operated from either end by means of a hand lever 4. At each side of the receptacle are located guides 5 on which are 50 adapted to move up and down slides 6, which are locked in their upper position by means of spring hooks 7 carried by the slides and adapted to engage catches 8 secured to receptacle 1. At the lower portion of each 55 slide 6, two bolts 9 are mounted to move horizontally in suitable guides, the inner

ends of such bolts having pins 10 projecting into spiral slots or cam slots 11, upon a rotary disk 12, which disk may be turned in one direction or the other by means of a handle 13. Thus the bolts may either be drawn inward as shown in Fig. 3, or shot outward as illustrated in Fig. 2. In the latter case, the outer ends of the bolts 9 will pass through eyes 14 at the ends of lever arms 15, which are secured to chain-wheels 16 loosely mounted upon the shaft 3 exteriorly of the receptacle 1. By means of chains 17, the wheels 16 are connected with another set of chain-wheels 18, secured to a shaft 19. This shaft is journaled in bearings 20, carried at the lower ends of bars 21, 22, secured to the receptacle 1. To the shaft 19 are also rigidly secured arms 23, 24, carrying at their free ends bearings 25, 26, for the 75 trunnion pins 27, 28, of a suspended hopper 29.

Immediately below the bottom opening of the receptacle 1, the bars 21, 22 on both sides thereof are connected by cross pieces 30 provided with inwardly projecting pins 31. Each of these pins extends through a longitudinal slot 32 of a guide-bar 33, which is secured to the side of a chute 34, so that the chute may be slid back and forth on the pins 31 immediately beneath the opening of the receptacle 1, and may also be tilted in one direction or the other. The tilting movement is, however, normally prevented by brackets 35 secured to the lower ends of the 90 slides 6 and engaging the chute 34.

The mechanism above described is operated as follows: The receptacle 1 having been filled with the material to be transferred into the retorts is brought adjacent to the retort 36 which is to be charged. Both slides 6 are supposed to be locked in their upper position by means of the hooks 7 and catches 8. The chute 34 is presumed to be in its central position; in other respects the parts occupy the position shown in Fig. 1. Then, presuming it is desired to charge the retort 36, the slide 6 shown at the right of Fig. 1 is moved down into the position shown in Fig. 1 and by turning the handle 13 on that side, the bolts 9 are projected into the slots 14 of the lever arms 15, and the chute 34 is pulled out to the left as shown, the bracket 35 preventing the chute from swinging on its pivots 31, notwithstanding the fact that the chute is no longer balanced. Then the slide 6 is moved upward again, and owing to the fact that the

bolts 9 are engaged with the arms 15, the chain-wheels 16 which are loose on the shaft 3 will be rotated. Through the medium of the chains 17 and wheels 18, this rotation is transmitted to the shaft 19, causing the arms 23 and 24 and the hopper 29 carried thereby to swing toward the left, so that the hopper will register with the retort 36, as shown in Fig. 4. At the same time the slide moves upward, the chute 34 is tilted as shown, owing to the fact that it is no longer held in a horizontal position by the bracket 35. Thereupon the shaft 3 is turned by means of either of the handles 4, so as to open the gate 2; whereupon the contents of the receptacle 1 will pass on to the chute 34 and through the hopper 29 into the retort 36. After the retort has been charged, the slide 6 at the right hand side is again lowered, which brings the chute 34 back to the position shown by solid lines in Fig. 1, and also swings the hopper 29 back to its central position. When it is desired to fill the retort 37, the operation is similar, only that the slide 6 at the left hand side is used, and the chute 34 is moved over toward the right. Fig. 4 shows in dotted lines the position of the various parts at the time of filling the retort 37.

The device described above is very simple in construction and operation and offers the further advantage that in the position of rest there are no parts projecting materially from the carriage, so that the device will not interfere with the travel of similar devices for adjoining rows of retorts.

The construction illustrated by Figs. 5 and 6 differs from the one described only by the means for operating the hopper 29. This hopper is suspended by means of a chain 38, secured to the arm 39 of a lever loosely supported on the shaft 3. This lever is provided with two additional arms 40 and 41 on the other side, the said arms having eyes 42 and 43 respectively, adapted to be engaged by the bolts 9 of one slide 6 or the other. The solid lines in Fig. 5, and Fig. 6, show the lever 39—40—41 connected with the right hand slide 6 so as to bring the hopper 29 into registry with the retort 36. The operation is substantially the same as described with reference to Figs. 1 to 4: That is, while one of the slides 6 is in its lower position, it is connected with the lever 39—40—41, by means of the bolts 9, and then the slide is moved upward to lower the hopper 29 on to the retort and to cause the chute 34 to tilt as shown in Fig. 6. The gate 2 is then operated by means of the handle 4, as previously described. When it is desired to charge the retort 37, the lever 39—40—41 is swung in such a manner that its arm 41 will be adjacent to the left hand slide 6, and the latter having been lowered is connected with said lever by means of the bolts 9, which position is indicated by dotted lines in Fig. 5. The chute

34 is moved over toward the right. Then the left hand slide 6 is raised, causing the hopper 29 to be lowered on the retort 37 and the chute 34 to tilt to the right.

Various modifications may be made without departing from the nature of my invention, as specified in the claims. By extending the parts which carry the hopper 29 and by an appropriate arrangement of the chute 34, three or more retorts or rows of retorts may be charged from the same carriage or receptacle. I prefer to so proportion the weights of the parts that either one of the slides 6 will balance the hopper 29 and the chute 34 to have an absolute or approximate equilibrium between these parts, so that they will be moved very easily.

I claim as my invention:

1. The combination of the receptacle having an outlet at the bottom, means for closing said outlet, a chute located beneath the outlet of the receptacle and mounted to be tilted in either direction, and a hopper movably mounted to take a position beneath the chute at either side of the receptacle.

2. The combination of the receptacle having an outlet and means for closing the same, with a chute located beneath said outlet and mounted to slide horizontally and also mounted to tilt in either direction.

3. The combination of the receptacle having an outlet and means for closing the same, with a chute located beneath said outlet and mounted to slide horizontally and also mounted to tilt, and means mounted on the receptacle, for normally preventing the tilting motion of the chute while allowing it to slide, said means being movable to release the chute for its tilting motion.

4. The combination of the receptacle having an outlet and means for closing the same, with a slide mounted on the receptacle, a hopper movable from a position of rest to an operative position, a chute for conveying the material from the receptacle to the hopper and means for connecting the slide with the hopper.

5. The combination of the receptacle having an outlet and means for closing the same, with slides mounted at opposite sides of the receptacle, a hopper movable from a central position of rest to operative positions at either side, a chute for conveying the material from the receptacle to the hopper and means for operatively connecting the hopper with one or the other of said slides.

6. The combination of the receptacle having an outlet and means for closing the same, with a slide movable vertically on the receptacle, a tilting chute located beneath the outlet and kept from tilting by engagement with the slide when the latter is in its lower position, a movable hopper arranged to cooperate with the chute, and an operative connection between the hopper and the slide.

7. The combination of the receptacle having an outlet and means for closing the same, with a slide movable vertically on the receptacle, a tilting chute located beneath the outlet and kept from tilting by engagement with the slide when the latter is in its lower position, means for locking the slide in its upper position, a movable hopper arranged to coöperate with the chute, and an operative connection between the hopper and the slide.

8. The combination of the receptacle having an outlet and means for closing the same, with slides mounted on opposite sides of the receptacle, a hopper movable from a central position of rest to operative positions at either side, a chute for conveying the material from the receptacle to the hopper a double-armed lever operatively connected with said hopper, and releasable means for connecting one of the slides with one of the arms of said lever, or the other slide with the other arm.

9. The combination of the receptacle having an outlet and means for closing the same, with a slide movable vertically on the receptacle, a tilting chute located beneath the outlet, and kept from tilting by engagement with the slide when the latter is in its lower position, a movable hopper arranged to coöperate with the chute, and an operative connection between the hopper and the slide, the slide being in approximate equilibrium with the chute and hopper coöoperating therewith.

10. The combination of the receptacle having an outlet and means for closing the same, with a chute for receiving the material from the receptacle rocking arms, and a hopper pivoted thereto and arranged to receive material from the chute.

11. The combination of the receptacle having an outlet and means for closing the same, with a chute arranged beneath the outlet, rocking arms, and a hopper hung on said arms and arranged to receive material passing out of the receptacle over the said chute.

12. The combination of the receptacle having an outlet and means for closing the same, with a chute for receiving material from the receptacle a hopper arranged to receive material from the chute, arms carrying said hopper, a rock shaft on which said arms are mounted, and means for swinging the rock shaft.

13. The combination of the receptacle having an outlet and means for closing the same, with a chute for receiving material from the receptacle a hopper arranged to receive material from the chute, arms carrying

said hopper, a rock shaft which is mounted below the receptacle and carries said arms, and means for swinging the rock shaft.

14. The combination of the receptacle having an outlet and means for closing the same, with slides movable up and down on opposite sides of the receptacle, means for locking said slides in their upper position, a tilting chute mounted to slide beneath the receptacle, said chute being prevented from tilting by engagement with one or the other of the slides when the latter is in its lower position, a rocking lever, means for coupling it with one slide or the other, a sprocket wheel secured to said lever, a shaft parallel to the axis of said lever, another sprocket wheel on said shaft, a chain engaging both sprocket wheels, arms on said shaft, and a hopper hung on said arms and arranged to coöperate with the chute.

15. The combination of the receptacle having an outlet and a swinging gate for closing the same, with slides movable up and down on opposite sides of the receptacle, a tilting chute mounted to slide beneath the receptacle, said chute being prevented from tilting by engagement with one or the other of said slides when such slide is in its lower position, a lever mounted loosely on the shaft of the swinging gate, a rock shaft parallel with the gate shaft and operatively connected therewith, and a swinging hopper operatively connected with said rock shaft and arranged to receive material from the chute.

16. The combination of the receptacle having an outlet and means for closing the same, with a lever fulcrumed on the receptacle, a chute arranged to receive material from the receptacle a hopper arranged beneath the chute, and a connection for suspending said hopper from the lever.

17. The combination of the receptacle having an outlet and a swinging gate for closing the same, with slides movable up and down on opposite sides of the receptacle, a tilting chute mounted to slide beneath the receptacle, said chute being prevented from tilting by engagement with one or the other of said slides when such slide is in its lower position, a lever mounted loosely on the shaft of the swinging gate, and a movable hopper connected with said lever to be shifted to different positions.

In testimony whereof, I have hereunto signed my name in the presence of two subscribing witnesses.

MAX BITTRICH.
